UNITED STATES PATENT OFFICE.

WILLIAM H. O. TAYLOR AND JOHN W. WAILES, OF PANTEG, COUNTY OF MONMOUTH, ENGLAND.

APPARATUS FOR CASTING METALS.

SPECIFICATION forming part of Letters Patent No. 224,245, dated February 3, 1880.

Application filed February 8, 1879.

To all whom it may concern:

Be it known that we, WILLIAM HENRY OSBORNE TAYLOR and JOHN WILLIAM WAILES, both of Panteg, in the county of Monmouth, England, have invented certain Improvements in Apparatus for Casting Metals, of which the following is a specification.

Ring-shaped ingots and other annular or circular castings are ordinarily made by casting the metal in a mold furnished with a central core of sand or other suitable material.

Many disadvantages exist in this method of casting, one of the chief of which is that if the metal is thin it is often less sound than a block of solid metal, and great care must be taken in most cases to avoid the metal cracking as it contracts around the core.

To obviate these difficulties metal articles of the kind above named have been cast in molds, which are rotated at such velocity that the molten metal is driven to the outside of the mold by centrifugal force as it is poured therein, so that as the metal cools it becomes solidified in the form of a ring-shaped ingot or casting, the outer circumference of which takes the form of the interior of the mold.

The object of our invention is to provide for giving any required shape to the interior circumference of the casting; and to this end our invention consists in the combination, with such a rotary mold, of cores or plungers, which are contained within the mold, and which are adapted to move radially outward by the centrifugal force generated by the rotation of the mold, so as to impart the form of their outer sides or ends to the inner circumference or side of the ring or other casting.

In Sheet I of the accompanying drawings, Figure 1 shows a sectional elevation of a rotary mold, such as is usually employed in forming annular castings without a core, and a side elevation of driving mechanism for imparting motion thereto.

A is a vertical shaft supported in the standard B and carrying at its upper end the mold C. D is a band-pulley on the vertical shaft A, for receiving the driving-band E from a pulley, F, on the main driving-shaft G, which turns in bearings in the standard H. The mold C consists of a cylindrical box, which is

closed at top by a flat-faced cover, O'. This cover has a central opening, c, which leads, by radial or other passages, c', to a little distance beyond the inner periphery of the box C, for the purpose of supplying the molten metal thereto.

The cover will be held in place by means of steadyng-pins c², or their equivalent. On rapid rotary motion being imparted to the mold molten metal will be discharged into the central opening in the cover, and by its gravity the metal will find its way into the mold. Here, by the action of centrifugal force, it will be held in contact with the inner periphery of the mold and form a ring, as at Z, within it.

By keeping up the rotary motion of the mold until the metal has had time to set a ring will be formed with parallel, or nearly parallel, sides, and without the use of a core. The metal will therefore be free to contract in cooling without risk of cracking, and as no air can possibly be imprisoned within the metal the casting must necessarily be sound throughout.

When it is desired to gage the thickness of the annular casting, or to give to the inner periphery a special form, we employ a composite expanding core, which, under the action of centrifugal force, will be held against the metal and gage it to the requisite diameter, giving it at the same time, if desired, a special form.

In Sheet II of the drawings, Fig. 2 shows, in transverse section, and Fig. 3 in plan view, a mold prepared to cast flanged tires by the aid of centrifugal force, such mold being also fitted with an expanding core. This core is composed of segment-shaped pieces I I, the ends of which are chamfered inward to receive wedge-shaped filling-pieces I' I'. By preference these pieces I I' are formed of cast-iron; but other heavy material which will not be affected by the heat of the molten metal may be employed. The segment-pieces I and the wedge-pieces I' (at their apex) are rabbeted at their lower edge to bear against a shoulder, c³, formed on the bottom of the mold C, which shoulder gages the thickness of the casting by limiting the advance of the pieces constituting the composite core. The centrifugal

force generated by the rapid rotation of the mold will hold the core expanded against the pressure inward of the molten metal, which is admitted to the mold through the runners in the cover C', as above explained.

The metal in cooling will contract upon the core, forcing inward toward the axis of the mold the wedge-shaped pieces I' I', and thus any resistance by the core to the free contraction of the metal will be avoided.

In adapting the invention to other articles than annular castings the molds are arranged radially in a mold-box or on a table or frame, to which rapid rotary motion is imparted while the molten metal is being poured into the molds from a central supply.

The castings in these radially-arranged molds may be compressed by means of a movable plug or core having any form or shape that may be found necessary, such plug or core serving, like the expanding core in Figs. 2 and 3, to resist the motion inward of the molten metal, it being held in position by centrifugal force.

Fig. 4 shows a sectional elevation, and Fig. 5 a plan, of an arrangement of rotary mold-box for casting projectiles from metal under pressure.

In this box, K K are the molds for the projectiles. These molds are formed in sand, with open ends, and arranged so that their axes radiate from the center of motion. In rear of the open end of each mold is a cylindrical extension, L, which forms a guide for the reception of a cylindrical plug or core of metal, M, that serves to close the end of the mold. These plugs or cores are held up to the molds by centrifugal force during the casting of the projectiles and setting of the metal.

The cover C' of the mold-box C has formed in it runners c', leading from the central opening, c, which runners are continued into the sand, so as to supply the molten metal to the extreme end of the mold.

The molten metal, as it is poured into the

central opening, c, will, by reason of the centrifugal force imparted to it, be driven, first, toward the circumference, and then into the molds, pressing back, or tending to press back, the plungers or cores, which, however, will be pressed forward by the centrifugal action imparted to them. Thus the casting will be more homogeneous and free from honey-comb or blow-holes than if cast in stationary molds; and pressure being maintained on the metal while setting, it will be condensed and its specific gravity consequently increased.

Having now explained the nature of our invention, we wish it to be understood that we claim—

1. The combination, with a mold for casting metals which is adapted to be rotated to generate centrifugal force, whereby the molten metal is carried to the outer periphery of the mold, where it solidifies, of cores or plungers which are loosely arranged within said mold, and which are forced radially outward by centrifugal force, to give shape to the inner circumference or side of the casting, substantially as and for the purpose specified.

2. The combination of the mold C, and the segments I and wedge-shaped pieces I', contained loosely within said mold, and adapted to be moved radially outward by centrifugal force generated by the rotation of the mold, substantially as and for the purpose specified.

Dated the 28th day of December, 1878.

W. H. OSBORNE TAYLOR.
JOHN W. WAILES.
